CLAIM

The ornamental design for a capo, as shown and described.

DESCRIPTION

FIG. 1 is a perspective view of a capo showing our new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The dash-dash-dash broken lines shown in the drawings are for the purpose of illustrating portions of the capo that form no part of the claimed design.

(Continued)

The dash-dot-dash broken lines shown in the drawings are for the purpose of illustrating boundaries of the capo and are not part of the claimed design.
